P. J. FOLEY

GREENHOUSE AND CONSERVATORY

Filed May 28, 1921

Philip J. Foley Inventor:
By Jno G. Elliott his Atty.

UNITED STATES PATENT OFFICE.

PHILIP J. FOLEY, OF CHICAGO, ILLINOIS.

GREENHOUSE AND CONSERVATORY.

Application filed May 28, 1921. Serial No. 473,451.

To all whom it may concern:

Be it known that I, PHILIP J. FOLEY, a citizen of the United States, and a resident of the city of Chicago, in the county 5 of Cook and State of Illinois, have invented certain new and useful Improvements in Greenhouses and Conservatories, of which the following is a specification.

This invention relates to improvements 10 in greenhouses and conservatories, provided with the standard type of channel beams for supporting their roofs and providing gutters for drainage purposes, and to which latter end their glazing projects 15 over and is supported by means of Z-shaped clips or bars bolted to and extending outwardly across the flanges of the beams, as shown in the drawing.

The standard type of channel beam has 20 for many years been largely used for supporting and providing drainage gutters for the glass roofs of greenhouses and conservatories because it is peculiarly adapted to perform both of these functions; it is readily obtainable on the market, kept in stock, 25 as it is, in large numbers; and has great strength and durability, combined with lightness and ease of installation and anchorage.

30 Notwithstanding the desirability of using the standard type of channel beams for the purposes above described, such beams are, nevertheless, subject to the objection that the condensations deposited thereon from 35 the glazed roof, together with accumulations on the external surface of the gutter, are distributed in the form of large beads detaching themselves and falling upon persons passing under them, to their discomfort and to the injury of their clothing, and more especially that these drippings are injurious to the flowers, fruits and vegetables 40 in their path, planted in a greenhouse, if for no other reason than that they produce spots and defects therein which it is necessary and desirable to avoid, if possible.

45 The object of my invention is to utilize all of advantages attributable to the use of the standard type of channel beam as a continued support and gutter for the roofs of greenhouses and conservatories, and, in addition thereto, provide a simple and effective means by which the accumulation of condensations on a channel beam are collected 50 and discharged thence directly outside of the building or to the ground within, at a

place where no harm is done to growing crops or persons.

More specifically stated, the object of my invention is a channel beam forming the 60 support and gutter for the roof of a greenhouse and conservatory, the under-surface of the web of which is so formed that the globules resulting from the accumulation 65 of condensations are caused to adhere thereto by capillary attraction, until they are conducted well towards the longitudinal side edges of the beam before they are discharged therefrom by gravity, and at such a point that they are collected and may be 70 discharged from the building in which such beams are located.

With these ends in view, my invention finds embodiment in certain features of novelty in the construction, combination 75 and arrangement of parts by which the said objects are attained, all as hereinafter fully described with reference to the accompanying drawings and more particularly pointed out in the claims.

Said drawing illustrates in cross-section 80 a channel bottom in which my invention finds embodiment.

Similar characters of reference indicate 85 the same parts in the drawing.

For carrying out my invention, a channel beam, provided with the usual opposing flanges 1 and 2, has its under-surfaces inclined upwardly, as indicated respectively at 4 and 5, the apex of which is indicated 90 at 6, which inclines extend to and terminate at the side edges of the beam, which is preferably angular, but may be somewhat curved and formed in the initial rolling of the beam or by bending inwardly the flat 95 bottom of the web of a standard channel beam.

The angle of inclination of the bottom surface of the beam is such that, as indicated 100 in the drawing, the water globules 4^a formed from the accumulation of condensations thereon and during their formation will be forced to travel in an outward direction across said surface, while in the meantime adhering thereto until they have arrived 105 well towards the extreme edges of the beam and at a point thereon immediately over receiving troughs 7—7, before being released by gravity from such surface for their discharge therein, which troughs are located 110 longitudinally of the beam and are not only adapted to collect, but to discharge their

contents outside of the structure in which they are located, or within, as hereinbefore stated.

The troughs 7-7 may be supported by 5 any suitable means therefor and so located that the accumulated condensations discharging from, and leakage through the roof of the structure will be conducted directly down the outer sides of the flanges 10 1 and 2, together with the condensations initially accumulating on and from the chilling effect on the surface of such flanges.

The new type of channel beam herein described is not only adapted to provide a 15 support and gutter when located between the edges of adjacent roofs, the glazing of which projects over the edges of the flanges of the beam and is maintained against downward movement by the usual Z-shaped 20 clips or bars 9-9, but for the eaves of a single house in the absence of a gutter for discharging the globular condensations downwardly next to the side wall thereof and out of the path of the plants below the 25 same.

For detachably locking the edges of the roof supporting the glazing to the flanges of the channel bar, and following my practice for a number of years, the bracket 10, 30 at the right-hand of the drawing may also be employed, which bracket, however, forms no part of my present invention.

By the use of my invention, a means is provided not only for effectively preventing 35 drops of water falling from the channel bar, but also those which are due to the accumulation of condensations on the under-surfaces of the glass roofing for greenhouses and conservatories from striking and 40 thereby causing spots and defects in the

growing flowers, fruits, vegetables, etc., planted therein below their channel beams.

In conclusion, it is to be observed that my invention not only successfully prevents the plants from being injured by the globules 45 of water dropping from the channel beam, due to their accumulation thereon, and on the roofs for which it forms a support and gutter, but, as compared with the standard type of channel beam, increases the strength 50 of channel bars, resisting their bending due to the weight of the roof supported by them.

Having described my invention, what I claim and desire to secure by Letters Patent is:

1. A channel beam the outer surface of the web of which is inclined downwardly from approximately its center of length to the side edges thereof.

2. A channel beam the outer surfaces of the web of which is substantially angular in cross-section throughout the length of the beam.

3. A combined support and gutter for the roofs of greenhouses and conservatories, 65 consisting of a channel beam the outer surface of the bottom of which converges upwardly from the side edges to approximately the center of length of said beam.

4. The combination with the roofs of greenhouses and conservatories, of a channel beam supporting and providing a gutter therefor, the under-surface of which inclines downwardly from approximately the center of length of said beam to the side edges thereof, and troughs located in a plane 70 immediately below said side edges.

In witness whereof, I have hereunto set my hand this 25th day of May, 1921.

PHILIP J. FOLEY.
